UNITED STATES PATENT OFFICE.

WILLIAM C. BAXTER, OF BEVERLY, MASSACHUSETTS, ASSIGNOR TO UNITED SHOE MACHINERY COMPANY, OF PATERSON, NEW JERSEY, A CORPORATION OF NEW JERSEY.

WORK-SUPPORT.

1,123,220.

Specification of Letters Patent.

Patented Jan. 5, 1915.

Application filed March 18, 1912. Serial No. 684,425.

To all whom it may concern:

Be it known that I, WILLIAM C. BAXTER, a citizen of the United States, residing at Beverly, in the county of Essex and State 5 of Massachusetts, have invented certain Improvements in Shoe-Supports, of which the following description, in connection with the accompanying drawings, is a specification, like reference characters on the drawings indicating like parts in the several figures.

This invention relates to shoe supports and has for its object to provide a support having improved facilities for presenting 15 the shoe held by it in position to be operated upon.

The invention is herein embodied in a support for holding a lasted and soled shoe in position for the shank to be beaten at 20 each lateral edge downwardly upon the bottom of the last which is at such time within the shoe, the purpose of the operation being to conform the shank of the shoe bottom to the transverse curvature of the last 25 bottom and to compact the materials of the shoe bottom so that in appearance they will present a minimum of thickness.

The beating machine illustrated is an adaptation of the machine shown in United 30 States Patent No. 768,560, granted Aug. 23, 1904 on application of Louis A. Casgrain, and in which the operation of the machine is dependent upon the maintenance of continuous contact between the work and the 35 beating tool.

The invention is herein embodied in a shoe support which is an improvement upon the shoe support shown in application of Louis A. Casgrain, Ser. No. 683,759, filed concur- 40 rently herewith.

The improvements constituting the features of this present invention will now be described in connection with the accompanying drawings and then particularly 45 pointed out in the claims.

Figure 1 is a front elevation of the machine equipped with the shoe support of the present invention. Fig. 2 is a perspective view of the shoe holder. Fig. 3 is a detail 50 of the vibration absorbing connection between the treadle and the jack spindle. Fig.

4 is a transverse vertical section of the toe rest. Fig. 5 is a longitudinal vertical section of the last pin. Fig. 6 is a detail of the last pin adjuster. 55

The column or frame has bearings for the two part spindle 2 the lower end of which is sustained by a toggle 4, 5, member 5 being pivoted to the column at 6 and having a horizontal arm 8 so that said member 60 is in effect a bell crank. Underlying the arm 8 is the arm 9 of a rock shaft 11 the other arm 10 of which overlies the rear arm of treadle 12. A spring 15 approximately balances the weight of the jack while a stop 65 13 limits the extent to which the spindle may be pressed down when a shoe on its last is placed in the holder. The described leverage between the treadle and the spindle affords ample advantage for holding the 70 shoe up to the pounding tool 100 which is rapidly reciprocated by impulses received from a rotary actuator as described in United States Patent No. 768,560, and at the same time said leverage connections absorb the 75 vibrations of the shoe holder sufficiently so that there is not an objectionable motion of the treadle upon which the operator must hold his foot while a shoe is being pounded. 80

A spring 16 is confined on the spindle between collars 17, 18 the latter of which is adjustable to vary the compression of the spring.

Upon the upper end of the spindle is a 85 bracket the arms 21 of which support the edges of a table 20 and through a large hole in the top of the table depends the stem 23 of a float 25, the stem carrying a foot plate 24 larger than the hole in the table and free 90 to slide around against the under side of the table in a recess 22 as appears in Fig. 1. This affords provision for free turning and also horizontal sliding movements of the shoe holder upon the table within the 95 limits of the hole in the table.

The float has rollers 26, 27, 28 between which is confined and guided the arc shaped foot 30 of the shoe holder, the same being curved substantially parallel with the curvature of the shank, see Fig. 1, of a standard shape of last so that the beating point 100

on the shank is maintained in approximately the same vertical relation to tool 100 as the beating progresses along the shank.

As thus far specifically described the machine is the invention of said Casgrain.

The heel clasp post 32 is fastened to the foot 30 and at its upper end is formed with a bearing for a rod 34 on which is fastened a handle 35. On the opposite end of the 10 rod is secured the segment plate 37 which rests on a rib 36 of the post and has in its inner face a guideway for the head pieces of the wing plates 70 of the heel clasp. Said plates are confined in the guideway by the 15 cap plate 73 and are adjustable for wide and narrow shoes by the adjusting screw 75.

To the segment plate 37 are also bolted at 38 the rear ends of supports in the form of rails 45 which extend forwardly to a transverse segmental slider 44 to which said rails 20 are secured at 48. The slider 44 is confined in a correspondingly shaped pathway in the top face of the toe clasp post or block 40 which is provided with slider supporting 25 rolls 42. The pathway and the slider are curved about an extension of the axis of rod 34 so that the supporting rails 45 and the parts supported by them can freely tip transversely of the shoe.

Upon the rear part of the rails 45 is supported the last pin carriage 50 which is held in adjusted position by a pin 51 that may be inserted in one of several pin holes in the front rail. The carriage supports the 35 screw rod 52 that carries the last pin 54 and can be adjusted by the nut 55 the top face of which has nut locking notches to be engaged by a combined spline and nut locker 56 the stem of which slides in a groove in the side 40 of the screw rod and the foot of which is pressed against the nut by a spring plunger 58.

Upon the forepart of the rails 45 is adjustable a toe rest carriage 60 in a hole in 45 which, Fig. 4, rests a sleeve 62 that is threaded to support adjustably the stem of a toe rest plate 64 upon which the toe rest 65 can slide freely transversely of the shoe to adjust itself to the position of the shoe 50 within the limits of a recess formed in the under face of the rest 65. This recess is entered by a stop pin 66 which also prevents accidental removal of the toe rest.

A forward extension 76 of the carriage 60 55 has a ratchet face and forms a guide and support for a toe abutment block 72 that has a downwardly and forwardly inclined, thickly padded shoe engaging face and can be thrust into position to abut against the 60 toe of the shoe and sufficiently overlie it to prevent the shoe from being lifted accidentally from the toe rest.

A combined handle and pawl 78 engages the ratchet face of extension 76 and holds 65 the abutment in adjusted position.

The construction of the shoe holder above described is an improvement upon that of Casgrain in that the combination of the heel post with the wings of the heel clasp affords added security of support which practical experience indicated to be needed, and prevents the wedging of the shoe down into the wings in a way to cause difficulty and sometimes injury in removing the shoe. The greater ease of adjustment of the toe 70 clasp for different sizes of shoes is also of advantage and a further important feature is found in the addition of the handle 35 by which the operator grasps the holder of the rear end of the shoe and turns the shoe 75 to present it accurately to the beating tool 100 and to vary the presentation as the operation progresses along the shank.

Having thus described my invention, what I claim as new and desire to secure by Letters Patent of the United States is:—

1. In a shoe support, a foot, a shoe holder mounted on the foot to permit movement about an axis extending lengthwise of and longitudinally through a shoe in the holder, a handle by which to effect and control movement about said axis, and means permitting movement of the shoe holder about an axis located above the shoe and extending transversely thereof.

2. In a shoe support, a foot, a heel clasp mounted on the foot, a rod extending lengthwise of the shoe and connected to the clasp at one end, and a handle on the other end of the rod and adapted to turn the clasp 100 about the axis of said rod.

3. In a shoe support, a foot, a heel clasp mounted on the foot, a rod extending lengthwise of the shoe and connected to the clasp at one end, a toe rest mounted on the foot 105 to move about the axis of said rod, a handle on the rod for turning it, and connecting means for causing the toe rest to be turned by the handle.

4. In a shoe support, a heel clasp comprising a back plate, wing plates adjustable transversely of the last from and toward each other on the back plate to clasp lasts of different sizes, supports connected with the back plate and a last pin carried by 115 said supports and adjustable longitudinally of the last between the wing plates.

5. In a shoe support, a foot and a shoe holder comprising wing plates to clasp and hold rigidly the heel end of the shoe and a last pin, all supported on said foot to turn with the shoe about an axis extending longitudinally through the shoe in the clasp.

6. In a shoe support a foot, end posts mounted on the foot, continuous rails mounted to turn relatively to said posts about an axis extending lengthwise through the shoe to be sustained, and a last pin and a toe rest carried by said rails for movement together about said axis.

7. In a shoe support, a foot, a toe post mounted on the foot and having a guideway therein curved about an axis extending lengthwise through the shoe to be sustained, 5 a block confined for movement in said guideway, supports extending heelward from said block, and a toe rest adjustable lengthwise of the shoe on the supports and which can move about said axis.
- 10 8. In a shoe support, a toe post, and a toe rest mounted thereon to turn about an axis extending longitudinally through the shoe and to slide freely relatively to said axis transversely of the shoe.
- 15 9. In a shoe support, a toe rest carriage, a sleeve therein, a stem having threaded engagement with the sleeve, a toe rest slidingly supported on the head of the stem, and a stop rod movable in the stem and co- 20 operating with the rest to determine the limits of movement of the rest.
10. In a shoe support a last pin carriage, a last pin, a screw rod supported in the car-

riage having a longitudinal groove in its side and supporting the last pin, an adjusting nut for said rod confined in the carriage and having nut locking notches in one end, and a combined spline and nut locker having a stem sliding in said groove and a foot engaging the locking notches in the nut. 25

11. In a shoe support, a foot, means permitting movement of the foot in a horizontal plane, a shoe holder mounted on said foot for movement about the longitudinal axis of the shoe, and means between the foot 35 and the shoe holder permitting movement of the shoe holder about an axis extending transversely of the shoe.

In testimony whereof I have signed my name to this specification in the presence of 40 two subscribing witnesses.

WILLIAM C. BAXTER.
